CLAIM

(57) The ornamental design for a radio charging station, as shown and described.

DESCRIPTION

FIG. 1 is a top, front and side perspective view of a radio charging station showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, facing perspective view with the lid in an open position;

FIG. 9 is a top plan view thereof; and,

FIG. 10 is a rear elevational view of the design of FIG. 1 showing the door in an open position.

The broken lines and areas within the broken lines depict environmental subject matter that forms no part of the claimed design.
